UNITED STATES PATENT OFFICE.

FRIEDRICH CONRAD BECK, OF SEUZACH, NEAR WINTERTHUR, SWITZERLAND.

ARTIFICIAL HAND.

1,347,004.

Specification of Letters Patent.

Patented July 20, 1920.

Application filed April 16, 1918. Serial No. 228,833.

To all whom it may concern:

Be it known that I, FRIEDRICH CONRAD BECK, a citizen of the Republic of Switzerland, residing at Seuzach, near Winterthur, 5 in the Canton of Zurich, Republic of Switzerland, have invented certain new and useful Improvements in Artificial Hands; and I do hereby declare the following to be a full, clear, and exact description of the invention, such as will enable others skilled in the art to which it appertains to make and use the same, reference being had to the accompanying drawings, and to letters of reference marked thereon, which form 15 a part of this specification.

The improved artificial hand according to the present invention is designed so that an effective grasping action is effected and comprises grasping members that are 20 adapted to be actuated by cords operated in any known way by reason of their connection with the natural arm left to the wearer.

The invention is clearly illustrated in the 25 accompanying drawings in which:

Figure 1 shows the inside of the right hand after the palm portion has been removed, and Fig. 2 is a detail view of the power-intensifying mechanism.

30 Fig. 3 is a side view of the artificial hand and of an artificial arm showing the connection of the hand with two stump muscles.

Figs. 4 and 5 are enlarged fragmentary 35 details of the power-intensifying mechanism.

Referring first to Figs. 1 and 2, 1 is the back of the artificial right hand, the inside 40 only of this back being visible. On the inside of the said back there are mounted two bearings 2 in which is fixed a stationary axle 3. On this axle 3 are mounted loose five cord pulleys 4, 5, 6, 7 and 8. These pulleys are freely rotatable independently 45 of one another but are unable to move axially. To each pulley 4-8 there is attached the end of a wire cord 9, 10, 11, 12 and 13. Of these wire cords, four, namely 9-12, are led from the top of the pulleys and 50 pass over guide pulleys 14 down to the guide pulleys 16 located on the inner finger sections 15, and thence to the points of attachment 17 on the outside of the end finger sections 18. The fifth wire cord 13 runs from the lower side of the pulley 8 and passes over a guide pulley 19

to a point of attachment 20 on the thumb. The wire cords 9-13 are led past the finger joints 21, 22, and the thumb joint 21^a respectively; they serve to close the hand or 60 to enable it to grasp articles. To each cord pulley 4-8 there is attached one end of a spring 23, the other end of which is fixed to the axle 3. The springs 23 are coiled in such a manner that they are stressed 65 when the pulleys 4-8 are rotated in the direction of the arrow y (Fig. 2).

The periphery of each cord pulley 4-8 is formed with ratchet teeth 24 engaged by a pawl bar 25. This bar is normally disengaged from the ratchet teeth of the cord pulleys 4-8, so that the latter are free to 70 rotate in the direction of the arrow y.

The ends of the pawl bar 25 are guided in slots 26 in extensions 27 of the bearings 75 2. On the right hand bearing 27 there is pivoted a lever 28 of long leverage which is movably jointed to the pawl bar 25 and upon whose end there acts a wire cord 30 passing over a pulley 29. The cord 30 is 80 connected by means of an ivory bar to one of the two muscles (preferably a stump muscle which has been previously adapted to serve as a source of power). A wire cord 31 coming from the second muscle branches 85 off into five branches 32, 33, 34, 35 and 36, of which the branches 32-35 pass behind the finger joints 21, 22 to the points of attachment 17 on the fingers, while the branch 36 passes behind the thumb joints 90 37, 21^a to the point of attachment 20^a on the thumb.

When the first mentioned muscle acts to pull the wire cord 31, that is to say, the branch cords 32-36, the fingers and the thumb are extended so as to open the hand completely, and simultaneously the springs 23 are stressed by the wire cords. As the pawl bar 25 is normally not in engagement with the pulleys 4-8, it can have a suitable 95 rotation. As soon as the article is within the range of the fingers this pull ceases, and then the stressed springs 23 effect a closing of the fingers and of the thumb. After this light grasping of the article which is also 100 adapted to the shape of the article, the last mentioned muscle pulling the wire cord 30, causes by means of the lever 28 the pawl bar 25 to be pressed with a force intensified by the leverage against the teeth 24 of the pulleys 4-8 (Figs. 2 and 4), and by this means 105 with a further but small rotation of the said 110

pulleys the fingers as well as the thumb are pressed tightly against the article being grasped so as to securely grip it.

The improved artificial hand may also be constructed in the form of what is known as a working hook. In order to produce a better grasping action, the palm of the hand is preferably provided with a pad whose thickness may vary with the object in view.

Moreover, the entire transmitting mechanism may be arranged nearer to or inside the wrist for the purpose of providing more abundant padding. Instead of two muscles only one muscle may be utilized for operating the improved artificial hand, by providing a sort of switch mechanism which causes the first pull of the muscle to act upon the wire cord 31, a second pull to act upon the cord 30 and the lever 28, and a third pull to act upon the cord 31, etc.

Any other mechanisms may be employed in place of the one shown, for the purpose of intensifying the applied power.

Instead of using toothed pulleys, racks may be employed which are connected with springs acting in the same sense as hereinbefore described and which are operated by a power-intensifying lever with a pawl bar as above described.

30. What I claim is:

1. In an artificial hand, the combination with joined fingers thereof, of a series of pawls and ratchets located centrally of the artificial hand, connections attached to said fingers and to said pawls and ratchets, and a tensile connection attached to said pawls and ratchets, whereby the patient by energizing said tensile connection, is able, by operating said pawls and ratchets to cause said fingers to hold the grasped article with an optional gripping pressure that is independent of the size or shape of the article to be held.

2. In an artificial hand the combination with joined fingers thereof, of a tensile connection attached to said fingers and to a source of power, a mechanism including a series of pawls and ratchets located in the artificial hand, a connection attached to said fingers and to said mechanism, and a tensile connection attached to that mechanism whereby the patient by energizing the first herein mentioned tensile connection is able to bend the artificial fingers into a grasp that is

more or less closely conformed to the contour 55 of the article to be held, and then by energizing the second herein-mentioned tensile connection is able, by operating said mechanism to cause said fingers to hold the grasped article with an optional gripping pressure that 60 is independent of the size or shape of the article to be held.

3. In an artificial hand, the combination with jointed fingers thereof, of an equal number of pulleys rotatable freely and independently of one another, a common axle for same mounted in the artificial hand, a ring of ratchet teeth on each pulley, a common pawl bar, a plurality of pawls on said pawl bar each engaging the ratchet teeth on its respective pulley, a plurality of cords each attached at one end to, and adapted to be wound on and off each of said pulleys, and attached at its other end to a finger of the artificial hand, and power-transmitting means for operating said common pawl bar, whereby on said bar being operated to pull said cords extra tight, the attached finger will be pressed with extra pressure against the article held by the artificial hand.

4. In an artificial hand, the combination with jointed fingers thereof, of an equal number of pulleys rotatable freely and independently of one another, a common axle 85 for same mounted in the artificial hand, a ring of ratchet teeth on each pulley, a common pawl bar, a plurality of pawls on said pawl bar each engaging the ratchet teeth on its respective pulley, a plurality of cords 90 each attached at one end to, and adapted to be wound on and off each of said pulleys, and attached at its other end to a finger of the artificial hand, a lever pivoted at one end to said pawl bar, and a common cord attached 95 to the other end of said lever, whereof on said common cord being pulled, the cords of the said pulleys are pulled with intensified force and thereby the fingers are pressed with intensified pressure against the grasped 100 article.

In testimony whereof I have signed my name to this specification in the presence of two subscribing witnesses.

FRIEDRICH CONRAD BECK.
